ATTORNEY

UNITED STATES PATENT OFFICE.

BIRGER ISIDOR RYDBERG, OF WESTANFORS, SWEDEN.

WRENCH.

SPECIFICATION forming part of Letters Patent No. 623,337, dated April 18, 1899.

Application filed March 17, 1898. Serial No. 674,160. (No model.)

To all whom it may concern:

Be it known that I, BIRGER ISIDOR RYDBERG, a subject of the King of Sweden and Norway, residing at Westanfors, Sweden, have 5 invented certain new and useful Improvements in Adjustable Nipper-Wrenches, of which the following is a specification.

This invention relates to the class of wrenches wherein the two jaws of the wrench 10 have shanks or handles and are pivotally connected together like nippers or scissors and wherein one of the jaws is mounted to slide in the other and is operated by gear-teeth.

The object of the invention is partly to 15 adapt the sliding jaw of the wrench for adjustment to nuts of different sizes. Other features of the invention will be hereinafter indicated, and the novel features thereof carefully defined in the claims.

20 In the accompanying drawings, Figure 1 is a sectional side elevation of the wrench, showing the jaws open. Fig. 2 is a similar view showing the jaws closed, and Fig. 3 is an edge view of the wrench as seen from the left in 25 Fig. 2. Fig. 4 is a side view of the head of the open wrench seen in Fig. 1. Fig. 5 is a section through the rivet or stud pivotally connecting the shanks of the jaws. Fig. 6 is a view illustrating the positions of the parts 30 when the movable jaw is to be adjusted.

35 1 is the fixed jaw, provided with a shank 2. The movable jaw 3 has a slide-rack 4 fixed to it and projecting at right angles from its face, this slide-rack having a guideway formed in the cheeks of the jaw 1, whereby the movable jaw is adapted to move up to and away from the fixed jaw in a straight line. On the lower edge or bottom of the slide-rack 4 are teeth 7, which gear with teeth 6 on the round- 40 ed end of an operating-shank 5, pivotally connected with the shank 2 by a stud or rivet 2^a, fixed in the cheeks of the shank 2.

45 As herein shown, the shank 2 and the jaw 1 thereon are formed of two substantially like sections placed face to face and secured together by rivets 2^b, the shanks 2 being thus formed trough-like, as seen at the bottom of Fig. 3, to receive the shank 5.

50 The shank 5 has formed in its face, about the pivot-stud 2^a, an annular recess or groove 8, in which is a coil-spring 9, the ends of which bear, respectively, on the shanks 2 and 5.

This spring tends to open the jaws of the wrench.

In Figs. 1, 2, and 6 the section is taken along 55 the median line, where the two sections of the jaw 1 and shank 2 come together face to face.

In order to prevent the jaw 3 from being disengaged or from dropping out by the dis- 60 engagement of the teeth 7 of its rack from the teeth 6 on the shank 5, as might take place under certain conditions, a stop 7^a is provided at the extreme end of the slide-rack, this being effected by simply elongating the end 65 teeth on the rack, so that it cannot pass the teeth 6.

When the shank 5 is turned to the extreme position, (seen in Fig. 6,) the teeth 7 will be clear of the teeth 6 and the jaw 3 may be 70 moved or adjusted so as to put the teeth into engagement or gear in a way to adapt the jaws to nuts of different sizes—that is to say, by shifting the jaw 3 to the extent of one tooth to the right in Fig. 1, for example, the jaws 75 will fit a smaller nut. This adjustment is indicated in dotted lines in Fig. 1.

It will be noted also in Fig. 6 that when the shank 5 is turned to the position illustrated 80 a shoulder 10 thereon is brought into position to take behind the stop-tooth 7^a, and when the parts are in this position and the jaw 3 held fast the teeth will come into gear properly to set the wrench-jaws for the smaller-sized nuts.

85 When the jaws of the wrench have been brought together, as in Fig. 2, they may be held in this position by a hinged link 11 on one of the shanks taking over the extremity 12 of the other shank, as clearly shown.

Having thus described my invention, I claim—

1. In a nipper-wrench, the combination with the fixed jaw 1, its shank 2, and the operating-shank 5, pivotally connected to the shank 95 3 and having gear-teeth 6 on its end, of the movable jaw 3 having a slide-rack 4, mounted in a guideway in the fixed jaw, said slide-rack having teeth 7 which gear normally with the teeth on the operating-shank, but which may 100 be disengaged therefrom for adjustment of the movable jaw, as described, and having a longer stop-tooth 7^a, at the end of the slide-rack, to prevent the jaw 3 from becoming

wholly detached from the wrench, substantially as set forth.

2. In a nipper-wrench, the combination with the fixed jaw, its shank, and the movable jaw 5 having a slide-rack mounted in a guideway in the fixed jaw, said rack having teeth 7, and a longer terminal tooth 7^a, of the operating-shank 5, pivotally connected to the shank of the fixed jaw and having teeth 6, which normally engage the teeth 7, and having also a

shoulder 10, which takes behind the long tooth 7^a when the wrench is being adjusted, substantially as and for the purposes set forth.

In witness whereof I have hereunto signed my name in the presence of two subscribing 15 witnesses.

BIRGER ISIDOR RYDBERG.
